ATTACHMENT FOR INTERNAL COMBUSTION ENGINES

Max Dach, Flushing, N. Y.

Application March 2, 1934, Serial No. 713,653

6 Claims. (Cl. 192—3)

This invention relates to an internal combustion engine and is particularly useful when such engines are used for driving motor vehicles.

By this invention the danger of black or unburned exhaust gases escaping from the engine when the vehicle is being decelerated is greatly decreased or entirely avoided automatically without necessitating any conscious effort on the part of the driver for that purpose, a considerable economy in the consumption of gasoline and oil is effected, and the dilution of crank case oil with gasoline is decreased.

In carrying out this invention a tubular air inlet is provided for the inlet or suction manifold of the engine and two valves in series are provided in this inlet. One of these valves is controlled by the speed of the engine and adjustments may be made so that it remains closed so long as the speed of the engine is below a predetermined minimum. The other valve in the air inlet is closed while the engine is idling or is in normal operation at either high or low speed. Provision may, however, be made for opening it automatically to some extent at high speeds to cause air or steam vapors to enter the intake manifold. It will ordinarily be opened when the operator applies the foot brake.

So long as one or both of these valves is closed, air from the atmosphere is prevented from reaching the inlet manifold through the air inlet above mentioned, but air freely enters this manifold when both of said valves are open, thus breaking the vacuum and causing the mixture from the regular air inlet and the carburetor to cease flowing into the inlet manifold during the period when the two valves are open.

Means may also be provided by which the ignition is automatically cut out when not needed during the time no mixture of air and fuel is entering the inlet manifold.

The invention will be understood from the description in connection with the accompanying drawing in which Fig. 1 is a side view of an internal combustion engine with the attachment in place; Fig. 2 is a section on an enlarged scale through the attachment; Fig. 3 is a side view of the attachment; Fig. 4 is a section partly broken away showing some of the details; Fig. 5 is a sectional view of a modification; and Fig. 6 is a section through an alternative device for operating one of the valves.

In the drawing reference character 1 indicates the block or casing of an internal combustion engine that is provided with an inlet manifold 2

with a connection 3 from a carburetor (not shown), and an outlet manifold 4.

In carrying out this invention a hole or opening is provided in the inlet manifold 2 and an inlet pipe or conduit 5 is attached by its flange 6 to the manifold over the opening, or a cylindrical or other shaped inlet is provided from the outside air into the inside of the inlet manifold in any other convenient way.

A valve 7, which may be a butterfly type valve, 10 is installed in the inlet 5 and is attached to a shaft 8 that is journaled in air-tight bearings in opposite sides of the inlet pipe 5 with both ends of this shaft 8 projecting short distances outside of the pipe or inlet. An arm 9 is attached to one 15 end of the shaft 8 outside of the inlet 5 and a link or other connection 10 extends from the arm 9 to a foot brake pedal 11 of the automobile so that the valve 8 is opened when the foot brake pedal 11 is operated.

Another valve 12, which may be either like the valve 7, or of a different type, is located in the inlet 5. The valve 12 is attached to the shaft 13 which extends through the inlet 5 and is journaled in air-tight bearings in opposite sides of the walls thereof. An arm 14 is attached to one 20 end of the shaft 13 outside of the inlet 5 and a link or connection 15 extends from this arm to a governor on the engine shaft (not shown). This governor may be any of the well known sorts 25 to which the link 15 or other valve operating mechanism may be connected so as to open this valve in accordance with the speed of the engine. The governor can be adjusted to operate the link 15 or other valve operating mechanism at 30 or beyond any desired predetermined speed. Such governors are not a part of this invention 35 and are therefore not illustrated.

An adjustable arm 16 (Fig. 3) is attached to the end of the shaft 8 opposite the arm 9 and is 40 provided with a wiping contact 17 at its outer or free end. A toothed sleeve 18 of insulating material is secured to the extending end of the shaft 8 (Fig. 4) and a washer 19 of insulating material and a nut 20 are also provided as shown. 45 The opening in the arm 16 which fits over the shaft 8 is made large enough to extend over the sleeve 18 and is provided with teeth corresponding to the teeth on the sleeve 18 so that this arm may be put upon the shaft 8 at any desired 50 adjusted position.

An adjustable arm 21 like the arm 16 is attached to the extending end of the shaft 13 opposite the arm 14 and is provided with a wiping contact 22 at its free end. The arm 21 is con- 55

nected to the shaft 13 in the same way as the arm 16 is connected to the shaft 8.

The arms 16 and 21 are provided with binding posts 23 and 24 respectively that are electrically connected to the wiping contacts 17 and 22 respectively. Branches 25 and 26 of a primary wire 27 are connected to the binding posts 23 and 24.

A metal bar 28 is secured on the outside of the inlet 5 and is insulated therefrom as indicated at 29 (Fig. 4). This metal bar 28 is located between the arms 16 and 21 in such a position that it is contacted by the contacts 17 and 22 when the valves 7 and 12 are closed. A binding post 30 is connected to the bar 28 and a lead wire 31 leads from this binding post to the distributor (not shown) of the engine. The ignition circuit is broken when the valves 7 and 12 are open.

A connection 33 may extend from a pivot on the arm 14 intermediate its ends to a pivot 34 on the lever 35 on the shaft of the distributor 36 so that the spark will be advanced and retarded in accordance with the speed of the engine.

In the modification shown in Fig. 5 the valve 12 is mounted to be opened in the opposite direction to the opening of this valve in Fig. 2. The arm 14 is provided with an extension 38 and carries an adjustable screw 39 near its outer end. The arm 9 is extended as indicated at 40 so that when the engine runs at a high speed the governor turns the arm 14 sufficiently to cause the screw 39 to contact with the portion 40 of the arm 9 and open the valve 7 slightly to admit air and thereby provide a leaner mixture of fuel and air at high speeds. The speed of the engine at which this takes place can be predetermined by setting the screw 39.

The valve 12 may be operated in accordance with the speed of the engine in other ways than by a governor driven by the engine. For example, the connection 15 may be connected to the piston rod 15' of a piston 41 that is moved by the change in the pressure of the oil in the crank case, as shown in Fig. 6. The piston 41 is in the cylinder 42 which is connected by the tube 43 to the cylinder oil which is under pressure when the engine is running. The cylinder 42 is provided with a screw cap 44 between which and the piston 41 a compression spring 45 is installed to return the piston when the oil pressure is released.

The operation is as follows:

While the engine is stationary or idling the valves 7 and 12 will be in the positions shown in Figs. 2 and 3. After the engine is started and as soon as it reaches a predetermined speed, which can be controlled by setting the governor to which the link 15 is attached, the valve 12 is opened but no air enters the inlet manifold 2 through the inlet 5 as the valve 7 is still closed. When the engine is running above the minimum speed that will open the valve 12 and the foot brake is applied, the valve 7 is opened, thus admitting air to the inlet manifold and breaking the vacuum. This causes a cessation of feed of the combustion mixture from the carburetor and thus saves fuel and avoids the danger of fumes escaping from the exhaust. As soon as the engine slows down below the minimum speed for opening the valve 12, this valve closes, thus stopping the entry of air through the inlet 5 so that the engine will continue to run at idling speed even if the clutch is thrown out. Also, when both valves 7 and 12 are opened the arms 16 and 21 turn to positions where the contacts 17 and 22 do not contact with the bar 28, thus cutting out the ignition. The

ignition will, however, be on so long as either valve 7 or 12 is closed.

Instead of having the valves 7 and 12 operated by link mechanisms 10 and 15, as illustrated, one or both of these valves may of course be operated in any other appropriate way.

I claim:

1. In an internal combustion engine, a vacuum breaking air inlet for the intake manifold of said engine, two valves in series in said inlet, one of said valves being opened by the operator and the other by said engine reaching a predetermined speed, said inlet and valves being of sufficient size to admit enough air to break the vacuum in said manifold, when said valves are open, sufficiently to cause the fuel mixture to cease flowing into the intake manifold.

2. In an internal combustion engine, a vacuum breaking air inlet for the intake manifold of said engine, two valves in series in said inlet, one of said valves being opened by the operator when he applies the brake and the other by said engine reaching a predetermined speed, said inlet and valves being of sufficient size to admit enough air to break the vacuum in said manifold, when said valves are open, sufficiently to cause the fuel mixture to cease flowing into the intake manifold.

3. In an internal combustion engine, a vacuum breaking air inlet for the intake manifold of said engine, two valves in series in said inlet, one of said valves being opened by the operator and the other by a connection to a governor on said engine, said inlet and valves being of sufficient size to admit enough air to break the vacuum in said manifold, when said valves are open, sufficiently to cause the fuel mixture to cease flowing into the intake manifold.

4. In an internal combustion engine, a vacuum breaking air inlet for the intake manifold of said engine, two valves in series in said inlet, one of said valves being manually operated and the other one being open at all times when the speed of said engine is above a predetermined minimum, said inlet and valves being of sufficient size to admit enough air to break the vacuum in said manifold, when said valves are open, sufficiently to cause the fuel mixture to cease flowing into the intake manifold.

5. In an internal combustion engine, a vacuum breaking air inlet for the intake manifold of said engine, two valves in series in said inlet, one of said valves being opened by the operator and the other by said engine reaching a predetermined speed, said inlet and valves being of sufficient size to admit enough air to break the vacuum in said manifold, when said valves are open, sufficiently to cause the fuel mixture to cease flowing into the intake manifold, and means whereby the ignition for said engine is cut off by opening said valves.

6. In an internal combustion engine, a vacuum breaking air inlet for the intake manifold of said engine, two valves in series in said inlet, one of said valves being opened by the operator and the other by said engine reaching a predetermined speed, said inlet and valves being of sufficient size to admit enough air to break the vacuum in said manifold, when said valves are open, sufficiently to cause the fuel mixture to cease flowing into the intake manifold, and means whereby the ignition for said engine is cut off by opening said valves, said means being adjustable with respect to said valves.
